(57) CLAIM

The ornamental design for a handbag organizer, as shown and described.

DESCRIPTION

FIG. 1 is a front, right side, top perspective view of a handbag organizer showing my new design;

FIG. 2 is a rear, left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front, right side, top perspective view of the handbag organizer when one of the components of the handbag organizer is removed from the handbag organizer. The broken lines depict portions of the handbag organizer that form no part of the claimed design.
